UNITED STATES PATENT OFFICE.

JOHN SHERMAN McCHESNEY, OF CHICAGO, ILLINOIS, ASSIGNOR TO J. S. McCHESNEY & CO., OF CHICAGO, ILLINOIS, A CORPORATION OF ILLINOIS.

WIRE-TYING APPLIANCE.

1,360,236.

Specification of Letters Patent. Patented Nov. 23, 1920.

Application filed November 18, 1916. Serial No. 130,941.

To all whom it may concern:

Be it known that I, JOHN SHERMAN McCHESNEY, citizen of the United States, residing at Chicago, Illinois, have invented 5 certain new and useful Improvements in Wire-Tying Appliances; and I do hereby declare the following to be a full, clear, and exact description of the invention, such as will enable others skilled in the art to 10 which it appertains to make and use the same.

My invention relates to packaging, and more particularly to means for rapidly, neatly and effectively using wire for banding or tying boxes, lumber, shingles, laths, pipes, or other objects. In using wire for such purposes, it has been customary heretofore to start with a cut length of wire and to intertwist the free ends of the wire with 15 pliers or the like, thereby leaving an unsightly projecting portion composed of the intertwined ends and apt to catch on other objects adjacent to the one around which the tie was formed. The difficulties of producing 20 a neat tie, of disposing the intertwined ends so that they would not catch on other objects, of manually tensioning the wire around the package, and of avoiding a waste in estimating the length of wire required 25 in each instance, have all mitigated against the use of wire for the general purposes mentioned, although wire has been admittedly cheaper than cordage of the same strength.

To overcome these difficulties, my invention provides a machine which uses the wire direct from the coil or reel, and which automatically compensates for variations in the periphery of the object packaged, and which 30 cuts off the wire when the tie is being finished, thereby reducing the waste to a minimum; to intertwist each end of the wire tie with a portion of the tie spaced from the other end, thereby affording a pair of twists 35 adapted to lie close to the package, to hold the initial wire loop in convenient position for inserting the desired object through it, to draw the wire around the object at the desired tension and to avoid overstraining 40 it, to automatically release the wire loop from its supports during the tensioning, to start the twisting automatically when the desired tension of the wire is reached; to 45 continue the twisting after the ends of the

wire have been severed, so as to turn the 55 free ends of the twists toward the interior of the package; to provide a machine for this purpose in which certain parts may easily be thrown into action; to provide for an easy and rapid manual manipulation of 60 the wire parts before the mechanically driven elements are set into operation, and to insure a stopping of certain of the elements in a position enabling an instant removal of the tied package and a ready placing 65 of the next wire portion; to provide means for holding the object which is to be packaged, and means for preventing overlapping portions of the wire loop from snapping out of their proper positions before the intertwisting is started; and to provide means for raising the wire-tied object clear of the mechanism. Other objects 70 will appear from the following specification and from the accompanying drawings, in 75 which—

Figure 1 is a plan view of a machine embodying my invention, with portions of wire loop and of the loop-support cut away.

Fig. 2 is a side view of the machine.

Fig. 3 is a fragmentary elevation of the shaft of the machine, showing the gear and cutters mounted on it.

Fig. 4 is an enlarged view showing portions of the clutch mechanism and of the 85 cam arrangement for operating the tensioning of the wire taken on the line 4—4 of Fig. 1.

Fig. 5 shows the position of the wire loop with respect to a package just before the 90 machine begins tensioning the wire; also, in dotted lines, the initial size of the wire loop.

Fig. 6 shows the finished wire band.

Fig. 7 is an enlarged section through the 95 gear of Fig. 1, showing the wire-twisting pinion and parts adjacent to the same.

Fig. 8 is an enlarged fragmentary view, 100 partially in section showing the clutch mechanism.

Fig. 9 is an enlarged fragmentary view of one of the latches which initially hold the lower portions of the wire loop in position.

Fig. 10 is an enlarged front elevation of 105 the clip which initially supports the upper portion of the wire loop.

In the embodiments of the drawings, my

appliance is shown in the form of a power-driven machine having a continuously rotating pulley 1 loosely mounted on a shaft 2 which shaft extends horizontally under a table 3 through bearings 4. The table 3 has an aperture (here shown as rectangular) through which a lifter frame 5 projects, this frame being movable by means of lifting fork 6 shown in Fig. 2. Disposed within 10 the frame 5 and normally projecting above it are guides 7, and a pinion 8 floatingly disposed between these guides and meshing with a spur gear 9 fast upon the shaft 2. The pinion 8 is equipped with a slot slightly wider than the diameter of the wire which is to be used on the machine, which slot extends (preferably radially) somewhat beyond the axis of the pinion, there being alined slots of larger diameter 15 in the guides 7. The shaft 2 also carries cutters 10 adapted during a certain part of each revolution of this shaft to project and operate through slots 11 in the table, the cutters being of such length that the uppermost portions of their paths will be substantially in line with the axis of the floating pinion 8. Mounted at the farther sides of the slots 11 from said pinion are pairs of spring jaws, each consisting of a fixed jaw 20 12 and a spring-actuated pivoted jaw 13, the tip of each pivoted jaw being so disposed with respect to its pivot as to resist the movement toward the pinion 8 of a wire extending from the slot in said pinion to the 25 said jaw. Still further to each side of the pinion 8 than the said spring clamps are spring clips 14, each desirably arranged as in Fig. 9 for holding a portion of the wire 30 15 under it, but permitting the spring plunger 16 to retract and release the said wire upon a sufficiently strong upward pull on the wire.

At the end opposite the pulley 1, the table 3 carries guideways 17 for a slide 18 carrying a pair of spring-pressed wedge jaws 19. The slide 18 is pivoted to one end of a thrust rod 20 extending under the table and projecting at its other end loosely through one arm of a bell-crank lever 21 pivoted to the table. This lever is connected to the rod 20 by a compression spring 22, the tension of which may be adjusted by nuts 23, and the other end of the lever carries a roller 24 bearing against the periphery of a cam 25 which is fast upon the pulley 1 and preferably integral with the latter. Fast upon the shaft 2 and adjacent to the cam 25 is a clutch body 26 carrying a plunger 27 adapted to project beyond the body 26 and 40 into engagement with a ratchet formation 28 on the cam 25, this plunger being continuously urged toward its said engaging position by a spring 29 acting on a piston 30 which piston is connected to the plunger 27 by a strap 31. The strap 31 preferably

is a portion of a ring concentric with the shaft 2, and has one end tapered, so that the tip of a release lever 32 may enter between this tip and the clutch body 26, as shown in Fig. 8, thereby moving the plunger 27 70 out of its said cam-engaging position. The lever 32 is preferably continuously urged in one direction by a spring 33, and has at its tapered tip a shoulder (shown in Fig. 4) adapted to engage one end of the strap 31 75 so as to stop a further rotation of the clutch body 26 after the tip of the lever 32 has entered between this body and the end of the strap 31.

In operation, wire is drawn from a coil 80 or reel (suitably disposed to the left of the machine in Fig. 2 but not shown in the drawing) and is formed into a loop having two of the lower portions overlapped and both slipped into the slot in the pinion 8, 85 the portion leading from the reel or coil being lowermost in the said slot but being then kept above the free end of the wire, which free end is butted against a low stop 34, as shown in Figs. 2 and 5. When thus 90 forming the wire loop by hand, the top of the loop is snapped between the jaws of a spring clip 35 supported by a gooseneck 45 mounted on the table 3, this gooseneck being so shaped as to bring the clip 35 directly 95 above the pinion 8. Other portions of the wire loop are snapped under the latches 14, and the free end portion of the wire is gripped by the right-hand spring jaws 12 and 13 so as to resist a tendency to pull the 100 tip of the wire away from the stop 34, while the portion of the wire leading from the coil or reel is clutched by the left-hand jaws 12 and 13, thereby preventing additional wire from being fed to the loop. Then the object to be tied is inserted in the loop, where it is held clear of the mechanism by posts 36 and is placed with one side against the riser 47, as shown in Fig. 2, after which the loop is partly tightened by hand by pulling 110 the coil end of the wire toward the left. Next, the coil end of the wire is slipped between the jaws 19 on the slide 18, so that the moving of this slide by the thrust rod 20 will cause the machine to effect a further 115 tightening of the wire, since every rotation of the cam 25 actuates this thrust rod through the agency of the lever 21 and the spring 22. Since the jaws 19 operate in the same direction as the left-hand spring jaws 120 12 and 13, the wedgily mounted jaws 19 may open on the returning movement of the slide 18, and as the jaws 12 and 13 will prevent the wire from slipping, the next movement of the slide toward the left will cause 125 the jaws 19 to take a fresh grip on the wire. Consequently, the rapidly repeated pushes of the rod 20 will continue to tighten the wire loop around the package until the tension of the spring 22 is reached, after which 130

the slide 18 remains stationary and the further movement of the lever 21 only serves to alternately compress and relax the spring 22. As soon as this point is reached (that is to say, as soon as the wire binding has been tensioned to the degree for which the spring 22 is adjusted by the nuts 23), the trip lever 32 is moved out of its stop position of Fig. 4, thereby permitting the plunger 27 to engage the ratchet formation in the cam and hence causing the continually revolving cam to rotate the shaft 2 with it.

A light spring 42 connects the rod 20 to the table and returns this rod after each thrust, besides aiding the spring 22 to limit the tensioning of the wire.

As soon as the shaft begins to rotate from its initial position of Fig. 7, the gear 9 turns the floating pinion 8 (which pinion is kept clear of the package by the posts 36), thereby twisting the overlapped wire portions at each side of this pinion. Meanwhile, the manually operated trip lever 32 has been released and the spring 33 causes it to hold its tip ready to wedge between the cam and the strap 31 when the cam has almost completed one revolution, thereby unlatching the clutch and allowing the clutch body, together with the shaft upon which the latter is fast, to be stopped by the engagement of a pin 50 on the clutch body with a shoulder 41 on the lever 32. To insure a continuing of the rotation of the shaft to the point at which the slot in the pinion is exactly vertical, so as to permit an easy release of the wire from the machine, I preferably mount on the shaft a weighted arm 37 so positioned with respect to the strap 31 that it will tend to force the rotation of the shaft until the pin 50 positively engages the shoulder 41 on the lever 32. Before the shaft reaches this stopping position, the cutters 10 (which, as shown in Fig. 7, are mounted in advance of the initial position of the shaft) shear off both of the lower wires of the loop as shown in Fig. 5; that is to say, one cutter clips a short piece off the free end and the other severs the loop from the supply portion of the wire. However, since the cutters are mounted in advance of the initial position of the shaft, the intertwisting of the overlapped wire portions continues after this cutting, thus turning the wire ends in the finished loop toward the interior of the loop as shown in Fig. 6. During this completion of the twisting, one of the cutters 10 pushes a slide 39 out of the way, thereby releasing auxiliary latches 38 which prevent the wire portions from slipping prematurely out of the slot in the floating pinion, this slide being returned to its operative position by a lever 40. When the tie is thus finished, the package may be raised by means

of the lifting fork 6, which causes the frame 5 to strip the wires out of the pinion 8; or, the package may merely be slid along on the posts 36 in case another loop is to be placed over it.

It will be evident from the above that after the wire loop has been manually disposed as in Fig. 2, the machine automatically performs the cycle of operations comprising the tightening of the wire to a predetermined tension, the forming of the two twists, and the cutting off of the twist ends at the proper time during the twisting operation, the releasing of the auxiliary latches 38 which keep the wires from slipping out of the slot in the pinion, the turning of the extreme wire ends toward the interior of the loop, and the stopping of the operative mechanism when the tie is finished. Moreover, since the posts 36 keep the pinion 8 clear of the object which is being wrapped and since the latches 38 prevent portions of the wire adjacent to the twists from being drawn against the object, my appliance may be used even with objects having a delicate surface, such as paper-wrapped packages. So also, if the object wrapped is incompressible, the loop after being completed may be slipped off the object (in a form shown for example in Fig. 6), so that my appliance may also be used for forming wire loops suitable for use as hoops, hose-bands or the like. In accordance with the provisions of patent statutes, I have described the principle of operation of my invention, together with the apparatus which I now consider to represent the best embodiment thereof; but I desire to have it understood that the apparatus shown is only illustrative, and that the invention can be carried out by other means.

I claim as my invention:

1. A wire loop closing machine, including means for holding the loop with each of its intended terminals overlapping a wire portion spaced from the other terminal, means for intertwisting each intended terminal portion with the wire portion overlapped thereby, and means for cutting off one of the said terminal portions, the cutting means being so timed in operation with respect to the twisting means that the cut end will be directed substantially toward the interior of the finished loop.

2. A wire loop closing machine, including means for holding the loop with relatively overlapped ends, means for tightening the loop to a predetermined tension, and means for thereafter intertwisting each end portion of the loop with the part of the wire adjacent thereto without relaxing the tension on the loop.

3. A package tying machine, including means for holding a wire loop with relatively overlapped ends, means for main-

- taining a package within said loop, and means for tightening the wire to a predetermined tension about the package subsequent to the formation of the loop.
- 5 4. A package tying machine, including means for holding a wire loop with relatively overlapped ends, means for maintaining a package within said loop, means for tightening the wire about the package 10 to a predetermined tension subsequent to the formation of the loop, and means for thereafter intertwisting two relatively spaced parts of the overlapped wire portions while the wire is under the said predetermined tension.
- 10 5. A package tying machine, including means for maintaining a wire loop around the package with two portions of the loop relatively overlapped, power-driven and 20 continuously reciprocating means for tensioning the wire around the package subsequent to the formation of the loop, and normally inoperative means for intertwisting a part of the relatively overlapped wire 25 portions operable subsequent to the tensioning of the loop.
- 30 6. A package tying machine, including means for maintaining a wire loop around the package with two portions of the loop relatively overlapped, power-driven reciprocating means for tensioning the wire around the package, and means for adjusting the last named means to vary the said tensioning.
- 35 7. A package tying machine, including means for holding a wire loop with relatively overlapped ends, means for maintaining a package within said loop, means for spacing the overlapped wire portions from 40 the package, means engaging a part of the wire portions thus spaced from the package and arranged for intertwisting a part of the said wire portions, and common means for actuating the last-named means and for 45 severing the wire adjacent to the twist, the severing means being arranged for operating approximately a half turn before the cessation of the twisting.
- 50 8. A package tying machine, including means for holding a wire loop with relatively overlapped ends, means for maintaining a package within said loop, means for spacing the overlapped wire portions from the package, means engaging a part of the 55 wire portions thus spaced from the package for intertwisting said wire portions, means for severing the wire adjacent to the twist, and means for discontinuing the intertwisting at a predetermined point after the said 60 severing.
- 65 9. In a wire loop forming machine, wire tightening means including a reciprocable slide, means carried by the slide for gripping the wire to move the same in one direction only, and means limited by a pre- determined tension of the wire for reciprocating the slide.
- 10 10. In a wire loop forming machine, wire tightening means including a reciprocable slide, means carried by the slide for gripping the wire to move the same in one direction only, a continuously reciprocated member, and connecting means interposed between said member and slide and including a spring arranged for rendering the 70 connecting means inoperative against the predetermined resistance to the movement of the slide.
11. A wire loop closing machine, including means for holding the wire loop with relatively overlapped end portions, fixed and rotatable means engaging parts of said overlapped wire portions, means for revolving the rotatable means to intertwist certain of the overlapped wire portions, latching 80 means for holding certain wire portions in operative relation with respect to said fixed and rotatable means, and means for releasing the latching means substantially at the completion of the intertwisting.
12. A wire loop closing machine, including means for holding the wire loop with relatively overlapped end portions, fixed and rotatable means engaging parts of said overlapped wire portions, means for revolving the rotatable means to intertwist certain of the overlapped wire portions, latching 85 means for holding certain wire portions in operative relation with respect to said fixed and rotatable means, and means for releasing the latching means.
13. A wire loop closing machine, including means for holding the wire loop with each of its intended terminals overlapping a wire 90 portion spaced from the other terminal, means for intertwisting each intended terminal portion with the wire portion overlapped thereby, and cutting means separate from the said intertwisting means for cutting off one of the terminal wire portions 95 adjacent to the resulting twist.
14. A wire loop closing machine, including means for holding the loop with each of its intended terminals overlapping a wire 100 portion spaced from the other terminal, means for intertwisting each intended terminal portion with the wire portion overlapped thereby, and means separate from the said intertwisting means for cutting off each terminal wire portion before 105 the completion of the intertwisting.
15. A package tying machine, including means for holding a loop of wire previously formed to the insertion of the package and 110 with terminal portions of the loop relatively overlapped, means for tightening the loop to a tension sufficient to cause the wire to bear flatwise against all sides of the package except the one opposite the said over- 115

- lapped wire portions, and means for thereafter uniting the said terminal portions.
16. A machine for wire-banding an angularly sectioned package, including means for disposing a loop of wire to receive the package and with portions of the loop relatively overlapped adjacent to one side of the package, means for tightening the loop subsequent to the insertion of the package, to a sufficient tension for causing the wire to indent the edges of the package, and means for intertwisting the overlapped wire portions while maintaining the tension on the loop. 60
17. In a package banding machine, a support for a package, wire-twisting means carried by the support, and means for holding a loop of wire in operative relation to the twisting means and disposed for inserting the package therein. 65
18. In a package banding machine, a support for a package, and means carried by the support for holding a loop of wire in position for inserting a package therein, the loop-holding means being adapted to be released by a tightening of the loop about the package. 70
19. In a package banding appliance, means for spreading a loop to a bore greater than the periphery of the package, and means for tightening the loop about the package, the said loop-spreading means being operatively released by the said tightening of the loop. 75
20. In an appliance for banding a package with a wire loop, a support for the package, and means carried by the support for determining the plane of the wire loop and holding the loop in such plane irrespective of the package. 80
21. In an appliance for banding a package with a wire loop, a support for the package, means carried by the support for determining the plane of the wire loop, and means for tightening the loop about the package, the said plane-determining means being so arranged as to be released by the tightening of the loop. 85
22. In an appliance for banding a package with a wire loop, a support for the package, means carried by the support for determining the plane of the wire loop, and means operating substantially in the said plane for tensioning the loop about the package and rendering a portion of said first means 90 inoperative.
23. In a package banding appliance, a support for a package, wire-twisting means carried by the support and including a rotatable pinion having a radial slot adapted to receive terminal portions of the proposed loop in overlapping relation; and a pair of grippers on opposite sides of the pinion and substantially in alinement with the said slot, for gripping portions of the wire loop to prevent enlargement of the latter. 95
24. In a package banding machine, wire twisting means, two wire gripping means substantially in alinement with the wire twisting means and respectively at opposite sides of the latter; and means for retracting the wire through the wire twisting means and through one of the said gripping means. 100
25. In a package banding appliance, a table arranged for supporting a package and having an aperture adjacent to the package, a wire twisting pinion rotatably mounted on the table and projecting upwardly through the said opening, and a gear disposed below the table and meshing with the pinion. 105
26. In a package banding machine, a support for a package, a rotatable wire-twisting pinion having a radial slot and mounted on the support for movement toward and from the package, and means for stopping the pinion in a position in which the slot is directed toward the package. 110
27. In a package banding machine, a support across which the banding wire is fed, means above the support for holding the upper portion of a loop formed from the wire, and means on the support for holding the terminal portions of the formed loop against enlargement of the loop but permitting the wire to slip therethrough for tightening the loop. 115
28. In a package banding machine, a support across which the banding wire is fed, means above the support for holding the upper portion of a loop formed from the wire, and means for twisting the terminals of the wire loop together. 120
29. A package banding machine comprising continuously operating loop tightening means including a slip joint operable to prevent effective operation of said means upon predetermined tightening of the loop. 125

Signed at Chicago, November 10th, 1916.

JOHN SHERMAN McCHESNEY.
